L. S. JOHNSON.
SELF HEATING SOLDERING IRON.
APPLICATION FILED AUG. 3, 1917.

1,260,200.

Patented Mar. 19, 1918.

UNITED STATES PATENT OFFICE.

LLOYD S. JOHNSON, OF DAYTON, OHIO.

SELF-HEATING SOLDERING-IRON.

1,260,200.

Specification of Letters Patent. Patented Mar. 19, 1918.

Application filed August 3, 1917. Serial No. 184,344.

To all whom it may concern:

Be it known that LLOYD S. JOHNSON, a citizen of the United States, residing at Dayton, in the county of Montgomery and 5 State of Ohio, has invented certain new and useful Improvements in Self-Heating Soldering-Irons, of which the following is a specification.

This invention relates to a combined blow 10 torch and soldering iron. The object of the invention is to provide a self-heating soldering iron the parts of which are compactly arranged to produce an efficient and easily manipulated device of this character. To 15 these ends the soldering iron in its entirety consists essentially of an elongated cylinder which constitutes the fuel reservoir, and an air pump extended into one end of said reservoir, and a burner on the other end 20 thereof with fuel-feeding devices on the interior of the reservoir and between the air pump and the burner and so constructed and arranged to provide an efficient feed of the fuel.

25 Referring to the accompanying drawings, Figure 1 is a horizontal longitudinal side elevation of my improved self-heating soldering iron. Fig. 2 is a horizontal longitudinal sectional view of Fig. 1 somewhat 30 enlarged and parts of which are broken out to facilitate space. Fig. 3 is a longitudinal horizontal sectional elevation of the device with parts broken away and the burner detached showing some modifications which 35 adapt the invention to the smaller size. Fig. 4 is a cross sectional view on the line 4—4 of Fig. 2. Fig. 5 is a cross sectional view on the line 5—5 of Fig. 1.

In the description to follow similar reference characters indicate corresponding parts 40 of the drawings. 1 designates a cylinder which constitutes the handle of the soldering iron and serves to contain the gasoline or other fluid from which the heat is generated. 3 is a cylinder which is projected into one end of the cylinder 1 through a stuffing box 5 which holds it in position. Within the cylinder 3 a pump cylinder 3'' is placed and held in position by a stuffing 45 box 6 which has a screw threaded engagement with the cylinder 3 and controls the removal of the pump cylinder 3'' when it becomes necessary to charge the cylinder 1 with gasoline. The cylinder 3 is provided 50 with a knurled operating member 4 which engages the screw threads of said cylinder 55 3 and by which it is turned in the stuffing box 5 to operate the needle valve 14 to be again referred to. The pump 3'' is adapted to furnish air to the interior of the cylinder 1 and the same contains a piston 8. There is an opening 9 in the bottom of said pump cylinder through which air is forced by said piston. The opening 9 is closed by 60 a suitable valve 10 which is held upon its seat by a coil spring 11. When the pressure of the air is sufficient the valve 10 is forced thereby from its seat and the air is discharged into the cylinder 1 through the opening 9. The cylinder 3 has an open extended portion 13 which terminates in a head or hollow member 12 to which the rod 14' of the needle valve is secured. The end 2 of the cylinder 1 opposite the pump 3'' terminates in a conical casting to the smaller 65 end of which a casting 3' is screwed, to be again referred to. 15 designates a stem, one end of which is screwed into the end 2 of the cylinder 1. The valve rod 14' passes through this stem 15 and the inner end of 70 the stem provides a guide for said valve rod. For a portion of its length the stem 15 on the interior thereof has a larger bore 15' into and through which the fuel or 75 gasoline passes to the chamber 23 in the casting 3'. The stem 15 has ports 18 and 19 in the side thereof and telescoped onto the stem 15 is a sleeve 16 which slides thereon according to the position of the soldering iron or cylinder 1. For example, 80 when the cylinder 1, as shown in Fig. 2, is moved to a vertical position with the pump end downward the sleeve 16 slides downward to the limit of its movement 85 which limit is measured by a stop 17 which 90 surrounds the inner end of the stem 15. The sleeve 16 has attached to it a pipe 21 that lies within the cylinder and is provided at its free end with a series of perforations 21' through which the fuel or 95 gasoline enters said pipe 21. At the point 100 where the pipe 21 is secured to the sleeve 16 it has the form of an elbow to which is secured a weight 22. The sleeve 16 has another inlet pipe 20 secured thereto which 105 has a weight 20'. These pipes 20 and 21 where they enter the sleeve 16 are adapted to communicate with one of the ports in the stem 15 and to thus conduct the gasoline or fuel to the interior of the stem 15. It 110 will be noted in Fig. 4 that there is a channel 18' in the stem 15 with which the ports

18 and 19 communicate so that the oil entering one of said ports will flow through the channel 18' and will enter the interior of the stem 15 through both ports. The effect 5 of the weights 22 and 20' on the pipes 20 and 21 is to cause said pipes to occupy a lower position so that they will communicate with one of the ports in the stem 15. As shown in Fig. 2 the inlet pipe 20 10 communicates with the port 19 in the stem 15. If the soldering iron as a whole is changed from its position as shown in Fig. 2 to a more or less inclined position or a vertical position the sleeve 16 will slide on the stem 15 and the pipe 21 will communicate with the port 19 in said stem, the purpose being 15 to provide for the feeding of the gasoline to the burner when the soldering iron is held in various positions by the hand. The 20 casting 3' constitutes the body of a burner. The needle valve has a screw threaded engagement with said casting 3' and as the cylinder 3 is turned by the finger piece 4 the needle valve is caused to regulate the 25 opening through which the gasoline is admitted. 25 is a needle valve which controls a passage 24 through which the gasoline is conducted from the chamber 23, the chamber 23, as before stated, being in communication with the passage 15' on the interior 30 of the stem 15. The passage 24 which, as before stated, is controlled by the valve 25, communicates with a passage 26. Extending from the passage 26 is a return pipe 27 35 the other end of which communicates with a passage 28 in the head or burner or casting 3'. The pipe 27 is inclosed in a cylinder 30, and said cylinder 30 is provided with air opening 29 through which air is 40 admitted to mix with the gas generated in the burner. In the initial operation of the soldering iron the needle valve 14 is removed from its seat to admit gasoline through the valve into an ignition pan 31, 45 a sufficient quantity of gasoline passing into said pan through an opening 32. The initial heat causes the liquid to gasify and the gasoline passing into the burner is vaporized by the heat of the burner. A soldering 50 iron or point 34 is secured to the burner and in alinement therewith by means of an extended arm 35 which is secured to the end of the burner cylinder 30 by a clamp 36. The soldering iron or point 34 has a flaring 55 end 33 which receives the heat generated in the burner and the attachment with the burner is made through a clamping member 37 which surrounds the soldering iron on the outside of the flaring end 33, the clamp 60 37 receiving the end of the pin or arm 35. In Fig. 3 the needle valve 14 controls the passage of the gas into the burner as the burner becomes sufficiently hot from the initial ignition of the gasoline admitted to the 65 cup 31. The form shown in Fig. 2 in which

the extra valve 25 is provided is intended for the larger sizes of soldering irons. Smaller sizes may be constructed in accordance with Fig. 3 of the drawing, in which case the extra valve 25 is eliminated. In 70 this case the needle valve 14 controls both the passage of gasoline into the burner and the resulting gas or vapor generated therefrom within the burner. The passage 23 in the end 2 communicates with a chamber 38 75 in the burner. The gasoline and the resulting gas passes from the chamber 38 through the return pipe 27 and into a chamber 39 from whence the gasoline passes out of the burner and into the ignition cup 31 through 80 port 32. The gasoline is initially admitted to the ignition cup 31 and after the burner has become sufficiently hot to generate gas the gasoline entering chamber 38 through the valve 14 is instantly generated into gas. 85

Having described my invention, I claim:

1. In a self-heating soldering iron, a cylinder adapted to contain fuel, an air pump communicating with said cylinder, a burner attached to said cylinder, a stem on the interior of the cylinder communicating with the burner, a needle valve extending through said stem into the burner and attached to said air pump, said stem having ports therein, a sleeve slidably supported on said stem, and feed pipes on the interior of the cylinder and attached to said sleeve and adapted to communicate with the ports in the stem depending upon the position of the soldering iron. 90

2. In a self-heating soldering iron, a cylinder adapted to contain fuel, a burner connected with said cylinder having a lateral passage, an auxiliary valve controlling said lateral passage, a pump extending into said cylinder, a stem within said cylinder communicating with the lateral passage in the burner, a needle valve extending through said stem and controlling the fuel after it is admitted through the lateral passage, a 105 sleeve slidably mounted on said stem, and feed pipes connected to said sleeve and adapted to communicate with ports in the stem whereby fuel is admitted to the lateral passage in the burner and thence to the needle valve. 110

3. In a self-heating soldering iron, a cylinder, an air pump communicating with said cylinder, a burner attached to said cylinder, a stem in said cylinder having a fuel 120 passage and ports communicating with the burner, a needle valve connecting with the air pump and passing through said stem and controlling the admission of fuel to the burner, a sleeve slidably mounted on 125 said stem, and feed pipes within the cylinder attached to said sleeve and adapted to communicate with the passage in the stem whereby fuel is discharged to the burner. 130

4. In a self-heating soldering iron, a cyl-

- inder adapted to contain fuel, an air pump communicating with said cylinder, a stem on the interior of said cylinder having a port and a passage through which the fuel 5 is conducted from the cylinder, a burner connected with said cylinder and providing a fuel chamber therein at the end of the cylinder which communicates with said stem, and a needle valve extending through 10 said stem into the burner and connected with the air pump.
5. In a self-heating soldering iron, a cylinder forming a handle and a reservoir for the fuel, an air pump communicating with 15 said cylinder, a stem in said cylinder having a port and passage forming an outlet from the cylinder, a burner connected with said cylinder and having a passage communicating with the stem, a needle valve controlling the outlet from the burner, a sleeve 20 slidably supported on the stem, and feed pipes on the interior of the cylinder and connected with said sleeve, said feed pipes being adapted to communicate with the port 25 in the stem whereby the fuel is conducted to the burner through said port and the needle valve.
6. In a self-heating soldering iron, a cylinder constituting a fuel reservoir, an air pump within one end of said cylinder, a 30 burner attached to the other end of said cylinder having a continuous fuel passage, a needle valve attached to the air pump and extended into the burner, and fuel feeding devices including a stem and a sleeve thereon on the interior of the cylinder controlling the passage of fuel to the fuel passage in the burner.
7. A cylinder constituting a fuel reservoir, an air pump extended into said cylinder, a burner attached to the end of said cylinder opposite the air pump and having a continuous fuel passage therein, an auxiliary valve in said burner controlling the initial admission of fuel, a needle valve controlling the discharge of the fuel, said needle valve being connected with a cylinder inclosing said air pump, a stem on the interior of the reservoir cylinder communicating with the fuel passage in the burner, a 40 sleeve slidably mounted on said stem, and weighted feed pipes connected to said sleeve and adapted to communicate with the passage in the stem according to the position of the sleeve on the stem. 45
- In testimony whereof I affix my signature.

LLOYD S. JOHNSON.
